UNITED STATES PATENT OFFICE.

GEORGE TOMKA AND SÁNDOR VARGA, OF SOUTH BETHLEHEM, PENNSYLVANIA.

DESIGN FOR A SIGN.

46,584.

Specification for Design.

Patented Oct. 20, 1914.

Application filed April 21, 1914. Serial No. 833,573. Term of patent 7 years.

To all whom it may concern:

Be it known that we, GEORGE TOMKA and SÁNDOR VARGA, subjects of the Emperor of Austria-Hungary, residing at South Bethlehem, in the county of Northampton and State of Pennsylvania, have invented a new, original, and ornamental Design for Signs, of which the following is a specification, reference being had to the accompanying drawing, forming part thereof.

The figure is a perspective view of a sign, showing our new design.

We claim.

The ornamental design for a sign, as shown.

GEORGE TOMKA.
SÁNDOR VARGA.

Witnesses:

C. A. GOSZTONYI,
EDW SYLVESTER.
